[57] CLAIM

The ornamental design for a hog feeder, as shown and described.

DESCRIPTION

FIG. 1 is a side elevational view of a hog feeder showing my new design;
 FIG. 2 is a front elevational view thereof;
 FIG. 3 is a top plan view thereof;
 FIG. 4 is an isometric view taken from the top, rear and one side of the base portion thereof; and
 FIG. 5 is a cross sectional view taken on line 5—5 of FIG. 3.

FIG. 5

FIG. 4
